UNITED STATES PATENT OFFICE

WILLIAM POOL, OF SPONDON, NEAR DERBY, ENGLAND, ASSIGNOR TO CELANESE CORPORATION OF AMERICA, A CORPORATION OF DELAWARE

TWISTING OF YARNS, THREADS, OR FILAMENTS

Application filed October 30, 1931, Serial No 571,970, and in Great Britain December 24, 1930.

This invention relates to the twisting of yarns, threads, or filaments (generally referred to hereafter as "threads") and in particular to twisting by means of devices adapted to impart more than one turn of twist for each revolution imparted to the device.

In such devices, the package from which the thread is to be wound does not partake of the revolution of the twisting device. The thread is drawn off the package and made to form a loop which is carried round the package itself by the rotation applied to the device. Assuming the package to be stationary, two turns of twist are imparted for each revolution of the loop about the package. Rotation of the package itself in a direction opposite to that of the loop enables a higher rate of twisting to be obtained for the same rate of revolution applied to the device.

According to the invention, a device of this character is employed to impart twist to two threads simultaneously, the two threads being drawn from a single package and led separately therefrom for each to be twisted to a larger number of turns than that imparted to the device.

Conveniently, the twisting is carried out by means of a device having tubular flyers as described in U. S. application S. No. 571,972 filed October 30, 1931, the threads passing from their package through separate arms of the flyer and out of the device at opposite ends, but any other twisting device enabling the threads to follow separate paths and to be led away at opposite ends may be used. In this manner, both threads are twisted to the same degree but in opposite senses.

In order to lead the two threads from the device, the device has a hollow spindle at each end, the flyers being connected to these spindles in such a manner that the threads can be drawn through the spindles and flyers without excessive tension.

Each spindle may be mounted in ball or other bearings, or the flyers may be made sufficiently strong to carry one spindle without the provision of a bearing for that spindle. The device is driven by means such as belt or other gearing or an electric motor coupled to the spindle. The package may be held sta-

tionary, or substantially so, by friction wheels carried bodily round by the driven spindle and engaging respectively a race on the package support and a fixed race independent of the package, as described in U. S. application S. No. 571,971 filed October 30, 1931. Alternatively, gears may be used instead of the friction wheels and races described above to keep the package stationary, and again, the gears or the friction device may be used to rotate the package, preferably in such a direction as will increase the rate of twisting. Gearing or friction wheels are particularly suitable for keeping the package stationary where the device is arranged with a vertical or substantially vertical axis, since in this case gravity cannot be utilized for this purpose as in devices having horizontal or substantially horizontal axes.

The threads on the single package may be already twisted threads, each of which can thus be given further twist. The invention is, however, particularly useful in enabling a thread of continuous filaments (e. g. of cellulose acetate, viscose, or other artificial silk, or natural silk) to be divided into two equal or unequal groups of filaments, each group then being twisted. Such thread preferably consists of untwisted filaments in order to make unnecessary the provision of untwisting means to enable the filaments to be separated ready for the retwisting.

The twisted threads may be collected by simple winding, preferably on separate packages, or may be further twisted, or doubled with other threads, by means of a suitable twisting device, such as a ring spindle. The degree of twist applied by the device depends, of course, on the rate of take-up and the rate of twisting, and may vary from low to high or very high according to the purpose to which the threads are to be put. If desired, the degree of twist may be caused to vary along the length of the thread by taking up the thread at an intermittent rate. Devices for this purpose are described for example in U. S. application S. No. 538,486, filed May 19th, 1931.

The invention will now be described in greater detail with reference to the accom-

panying drawing, but it is to be understood that this description is given by way of example only, and is in no respect limitative.

Figure 1 shows a sectional elevation of the device for carrying out the twisting operation according to the invention, the section being taken along lines 1—1 of Figure 2.

Figure 2 is a plan view of the device shown in Figure 1.

10 Figure 3 is a diagrammatic view showing the lay-out of the device shown in Figure 1, and

Figure 4 shows an alternate form of spindle driving device.

15 Referring to Figures 1 and 2, a bobbin 6 from which two threads 7, 8 are drawn, is mounted upon brackets 9, carried on a platform 10. The platform 10 is fixed to a hollow spindle 11, carried by means of ball bearings 12 in an enlarged portion 13 of a further hollow spindle 14. The spindle 14 is mounted in ball bearings 15 and is driven by means of a whorl 16. A short spindle 18 is supported by ball bearings 17 in the 20 enlarged portion 13 of the spindle 14, the spindle 18 being parallel to the axis of the spindle 14, and having gears 19, 20 fixed to its upper and lower ends respectively. The gear 19 meshes with a further gear 21 25 attached to the spindle 11 carrying the platform 10, while the gear 20 at the lower end of the spindle 18 meshes with a gear 22, rigidly fixed to the frame of the device. The gears 19 and 20 being of the same size, and the gears 21 and 22 being also of the same size, the rotation of the spindle 17 about the axis of the spindle 14 causes the gear 21 to remain stationary like the gear 22, with the result that the platform 10 and the package 30 6 are held stationary, and are not permitted to rotate with the spindle 14. The frame of the device to which the gear 22 is fixed rises in a flange 25 to enclose the gears 20, 22 and in a similar manner the enlarged portion 13 45 of the spindle 14 rises in a flange 26 to enclose the gears 19 and 21.

The enlarged portion 13 of the spindle 14, also carries two flyer tubes 27, 27', communicating with the hollow interior of the enlarged portion 13, the flyers passing out of the portion 13 from points lying at right angles to the points at which the spindles 18 are carried. For this reason the flyer 27' on the left of Figure 1 is shown in dotted lines, since this flyer is not actually cut by the sectional lines 1—1 of Figure 2. The flyers 27, 27' meet over the spindle in a connecting piece 28 mounted through ball bearings 29 in a tubular member 30 attached to the top rail 31 of the twisting device.

60 The threads 7, 8 leave the package 6 in opposite directions, the thread 7 rising to the connecting piece 28 and being passed down the flyer member 27' into the hollow interior of the enlarged portion 13, and thence down

the hollow spindle 14, after which it is collected on a package 32. The thread 8 passes downwardly from the hollow spindle 11, up through the flyer 27, and through the hollow connecting piece 28 to a second collecting package 33. In this manner the two loops of thread 34, 35 contained in the flyers 27, 27' follow entirely independent paths and rotate round the stationary package 6, as they are drawn therefrom.

70 Figure 3 shows the lay-out of the whole device, the threads 7, 8 leaving the opposite ends of the twisting device being passed through stationary guides 37 to traversing guides 38 by means of which they are led to take-up bobbins 32, 33. The bobbins 32, 33 are mounted in slotted bearings 39, and are driven by means of frictional rollers 40, engaging with the yarn of the packages 32, 33, so that the yarn is drawn from the package 6 at a constant rate, and collected on the packages 32, 33. A driving belt 41 engaging with the whorl 16 of the twisting device is also shown in this figure.

75 Figure 4 shows an alternative form of driving mechanism for the twisting spindle. The platform 10 is mounted on ball bearings 12, surrounding a spindle 43 which, has an enlarged portion 44 and is driven by means of a whorl 45. The enlarged portion 44 of the spindle 43 contains horizontal passages 46 leading to the flyers 27, 27', which are mounted on an annular ring 47 forming part of the enlarged portion 44. Disposed at points at 90° to the passages 46 are short spindles 48 carrying rollers 49 contained in recesses 50 in the enlarged portion 43. The rollers 49 are loosely mounted on the spindles 48, so that as the spindle 43 rotates the rollers fly outwards. Each roller 49 carries two flanges 51, 52 at the top and bottom respectively. The flange 51 engages with an annular depending race 53 rigidly fixed to the platform 10. The lower flange 52 engages with a similar annular race 55 carried by the frame 56 of the machine. Since the flanges 51, 52 are of the same size, the races 53, 55 are frictionally geared together, so that the upper race 53 is caused to remain stationary. As a result, the platform 10 of the bobbin 6 which is carried thereon, is caused to be held stationary while the spindle 43 and the flyers 27, 27' rotate, to produce the same effect as that described with reference to Figures 1—3.

100 What I claim and desire to secure by Letters Patent is:—

1. Method of twisting threads comprising drawing two threads from a single supply package, leading them in opposite directions to follow independent looped paths round the package, and rotating the loops about the package as the threads are drawn off.

105 2. Method according to claim 1, wherein

the rate of twisting is higher than the rate of rotation of the loops about the package.

3. Method of twisting threads comprising drawing two threads from a single thread of continuous filaments contained on a supply package, leading the two threads away from the supply package so as to follow separate looped paths round the package and rotating the loops about the package so as to twist each thread at a rate higher than the rate of rotation of the loops about the package.

4. Method of twisting threads comprising drawing two threads from a single un-twisted thread of continuous filaments contained on a supply package, leading the two threads away from the supply package so as to follow separate looped paths round the package and rotating the loops about the package so as to twist each thread at a rate higher than the rate of rotation of the loops about the package.

In testimony whereof I have hereunto subscribed my name.

WILLIAM POOL.
